(57) **CLAIM**

The ornamental design for a confection dispenser, as shown and described.

DESCRIPTION

This design patent application incorporates by reference in its entirety U.S. design patent application Ser. No. 29/746, 449, filed Aug. 13, 2020.

FIG. 1 is a top perspective view of a confection dispenser showing our new design in a closed position;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a top perspective view thereof showing our new design in an open position; and,

FIG. 9 is a right-side elevation view thereof.

The broken lines in the drawings illustrate portions of the confection dispenser that form no part of the claimed design.
